Inventor
Charles W. Cheney

By Attorney

UNITED STATES PATENT OFFICE.

CHARLES WILLIAM CHENEY, OF BIRMINGHAM, ENGLAND.

FASTENING FOR ATTACHE CASES, BOXES, BAGS, AND SUCH LIKE.

Application filed June 8, 1925, Serial No. 35,666, and in Great Britain July 18, 1924.

The invention relates to fastenings for attaché cases, boxes, bags or the like comprising two primary parts, one of which comprises a slidable bolt drawn back against 5 the action of a spring by manipulation of a slidable knob or boss carried by the face of this fastening part. The invention relates only to this fastener part. The other primary fastener part is usually a staple, 10 eye, or a notched stud adapted to be engaged by the bolt and sometimes carried by a fly-off hasp.

According to the invention said knob or boss is provided with a locking or blocking 15 device in the form of a revoluble piece which, when moved to one position prevents the drawing back of the knob or boss (and therefore the bolt), and, when moved to another position, permits said knob and bolt 20 to be freely drawn back. The blocking piece preferably forms a part of the knob or boss so as to partake of the sliding movement of the knob or boss but may be partly revolved on the knob or boss, independently 25 of movement of the latter, in order to effect the blocking and releasing action. The bolt is positioned between the front plate and the back plate of the fastening part and is connected through the front plate to the 30 knob or boss, an opening being cut through the front plate for this purpose. The blocking piece partly revolves about the knob or boss and has a stop which is movable in the opening of the front plate in either one of 35 two positions, one permitting the bolt to be drawn back, and the other preventing the movement of the bolt. The blocking piece may be a thin flat ring working between the underside of the knob and the face of the 40 front plate and having oppositely disposed, forwardly extending projections to lie over the boundary of the knob and form finger grips.

When the blocking piece is in position to 45 prevent the withdrawal of the bolt a part of it may lie over the hasp of the other fastener part to visually indicate that the bolt is blocked against movement.

Several embodiments of the invention are 50 shown in the accompanying drawings.

Fig. 1 is a front elevation of a fastening embodying one form of the invention.

Fig. 2 is a side view, partly in elevation and partly in section, of the fastening shown 55 in Fig. 1.

Fig. 3 is a front elevation, with the knob or boss removed, of the fastening part shown in Fig. 1.

Fig. 4 is a section on the line A—B, Fig. 3.

Fig. 5 is a side elevation of the knob or 60 boss and the blocking piece carried by it before application to the fastening part, Figs. 3 and 4.

Fig. 6 is a rear view of the parts shown in Fig. 5. 65

Fig. 7 shows the blocking piece separately and in vertical section.

Fig. 8 is a rear view of the blocking piece shown in Fig. 7.

Fig. 9 is a side elevation of the knob or 70 boss.

Fig. 10 is a back view of the knob or boss shown in Fig. 9.

Fig. 11 is a view similar to Fig. 1 showing a modified form of blocking piece. 75

Fig. 12 is a view similar to Fig. 3 of a modified form of the invention, the knob or boss being shown in position.

Fig. 13 is a side view, partly in section and partly in elevation of the fastener shown in 80 Fig. 12.

Fig. 14 is a front view, similar to Fig. 12, of another embodiment of the invention.

Fig. 15 is a section on the line C—D, 85 Fig. 14.

Fig. 16 is a rear view of the knob or boss and blocking piece shown in Fig. 15.

A fastening part, such as that to which the invention relates, frequently has a key 90 locking mechanism forming part of it, and this is indicated in the drawings by the key-hole and key post only, the key-hole in all of the illustrated embodiments of the invention, except one, being formed in the 95 knob or boss, and in that one through the front plate adjacent to the knob or boss.

Where permissible, similar letters of reference are used to indicate the same parts in all the figures of the drawings. 100

Referring to Figs. 1 to 10, *a* indicates one primary fastening part, and *c* the other primary fastening part. The part *c* is secured to the lid *d* of the attaché case or the like, and the part *a* to the body *e* of the attaché case or the like, in the usual way. The part *c* comprises an attachment plate *c*² to which is hinged at *c*³ a hasp, *c*⁴, carrying a staple for engagement by the bolt. 105

The fastening part *a* comprises front plate 110

a^2 and back plate a^3 between which the bolt f is mounted to slide. The bolt f has a nose end f^2 which slides across the slot a^4 of the front plate to engage the staple of the hasp c^4 of the part c . The spring for automatically shooting the bolt f is indicated at g . An opening h is formed in the front plate. The slidable knob or boss i is mounted on the face of the front plate to cover the opening h , and is rigidly connected through said opening to the bolt f by projections i^2, i^3 which extend through holes f^3, f^4 of the bolt and are clinched down at the back of the bolt as represented by Fig. 2. A key-hole j is formed in this knob or boss, which is hollow, to co-operate with a key post k on the bolt f . The aforesaid is all normal practice in such a fastening part.

The invention provides the knob or boss i with a locking or blocking device l in the form of a thin flat ring disposed between the underside of the knob i and the face of the front plate a^2 . This ring device is separately revoluble about the knob or boss but partakes of the knob's sliding movement with the bolt f . Projections l^2, l^3 of the ring device l extend forwardly of the latter and lie over the boundary of the knob to constitute finger grips, while a stop l^4 of said ring-like device works in the opening h of the front plate. The revoluble piece l is adapted to have a quarter of a revolution about the knob i , to bring its stop l^4 either into the position shown in Figs. 1 and 2 or into a position to abut against the back edge h^2 of the opening h . When the stop l^4 is in the position within the opening h shown by Figs. 1 and 2 the bolt f can be drawn back by a straight-line sliding movement of the knob or boss, carrying the blocking device l with it. If the blocking device l is revolved a quarter-turn to bring the stop l^4 against the abutment edge h^2 of the opening h the drawing back of the bolt f by the knob is blocked or prevented, giving efficient security, without key-locking, against the bolt being accidentally withdrawn.

The revoluble ring l is limited to a quarter-revolution engagement of a projection l^5 on its inner periphery against the two projections i^2, i^3 of the knob or boss.

It is to be understood that the fastening part need not be formed with a key locking mechanism, but preferably it has such.

Fig. 11 shows a fastening part similar to that shown in Figs. 1 to 10 except that the finger grip l^3 of the ring-like blocking device l is of extended length and is adapted, when the blocking device l is in bolt-blocking position, to lie over the fly-off hasp c^4 to visually indicate that the blocking device is in locked position, the device l , when in this position, being quite close to the face of the hasp.

Figs. 12 and 13 show a fastening part em-

bodying the invention wherein the key hole is not cut through the knob or boss i but through the front plate a to one side of said knob or boss.

Figs. 14 to 16 show a modified embodiment of the invention wherein the revoluble blocking device l is external of the knob or boss i , so that apparently the knob or boss itself partly revolves, which however is not the case, said knob or boss i being covered by the locking device and rigidly connected to the slidable bolt f by the projections i^2 and i^3 .

Having now described my invention, what I claim and desire to secure by Letters Pat- ent is:—

1. A fastening device comprising a casing having a front plate provided with a catch receiving slot, a bolt slidable in said casing and having a catch engaging nose, said front plate also having an opening adjacent said catch receiving slot, a knob slidable on the outer face of said front plate and having a part extending through said opening and fixedly secured to said bolt, and means mounted on said front plate in advance of said opening and rotatable relatively to said knob, said means adapted, when partly rotated in one direction, to engage a wall of said opening and prevent movement of said knob. 95

2. A fastening device comprising a casing having a front plate provided with a catch-receiving slot, a bolt slidable in said casing and having a catch-engaging nose, said front plate also having an opening adjacent said catch-receiving slot, a knob slidable on the outer face of said front plate and having a part extending through said opening and fixedly secured to said bolt, and rotatable means between said front plate and knob and adapted, when partly rotated in one direction, to engage a wall of said opening and prevent movement of said knob. 100

3. A fastening component comprising a casing having in its front face an opening and a catch-receiving slot, a bolt slidable in said casing and having catch-engaging means movable across said slot, a knob for actuating said bolt slidably mounted on the front face of said casing and having a part extending through said opening and secured to said bolt, and a blocking device for said knob rotatable relatively to said knob and having a finger grip extending laterally of said knob adapted, when the bolt is in engagement with a catch inserted in said slot, to lie over said catch and indicate that the bolt is in engagement with said catch. 115

4. A fastening device comprising a casing having a front plate provided with a catch-receiving slot, a bolt slidable in said casing and having a catch-engaging nose, said front plate also having an opening, a knob having a plurality of fingers extending through said opening and secured to said bolt, and a ring 125

rotatably mounted on said fingers between said knob and said front plate and having means extending into said opening adapted, when said ring is partially rotated, to engage a wall of said opening to prevent slidable movement of said ring and knob.

5. A fastening device according to claim 2

wherein the rotatable means has a finger-grip extending over the knob for actuation of said rotatable means.

10 In testimony whereof I have hereunto set my hand.

CHARLES WILLIAM CHENEY.
